DESIGN FOR A DRESS

Charles L. Calisch, Chicago, Ill.

Application February 1, 1941, Serial No. 98,635

Term of patent 3½ years

To all whom it may concern:

Be it known that I, Charles L. Calisch, a citizen of the United States of America, residing in Chicago, county of Cook, and State of Illinois, have invented a new, original, and ornamental Design for a Dress, of which the following is a specification, reference being had to the accompanying drawing, forming part thereof, where-

I claim:

The ornamental design for a dress, substantially as shown.

CHARLES L. CALISCH.
